UNITED STATES PATENT OFFICE

2,484,993

ROTARY PUMP

Milan Gruber, Aliquippa, Pa.

Application June 4, 1946, Serial No. 674,295

1 Claim. (Cl. 103—136)

1

This invention relates to rotary pumps in which an eccentrically mounted rotary drum carrying a plurality of cylindrical roller pistons operates within a stationary pump housing.

One of the main objects of the present invention is to provide a rotary pump in which the cylindrical roller pistons are not depending on centrifugal force in order to create suction within the pump housing, such as is the case with nearly all pumps of that type.

Another object of the invention is to provide a rotary pump in which the cylindrical roller pistons always uniformly contact the inner peripheral bore of the pump housing, while the eccentrically mounted drum in which said roller pistons operate rotates.

Still another object of the invention is to provide a rotary pump with an eccentrically mounted drum in which a plurality of cylindrical roller pistons freely rotate and which are in uniform continuous contact with the inner peripheral surface of the pump housing by means of a freely inserted cylindrical spring-member.

Yet another object of the invention is to provide a rotary pump which may be reversed without resorting to any alterations.

Another object of the invention is to provide a rotary pump which may be operated at slow speed and which will pump liquid almost immediately after the piston retaining drum is being rotated.

Further objects of the invention are to provide a rotary pump of the class set forth that shall be of exceedingly simple construction and arrangements, efficient in its operation and which can be inexpensively manufactured.

To the accomplishment of these and such other objects as may hereafter appear, the invention consists of the novel construction, combination and arrangement of parts herein specifically described and illustrated in the accompanying drawing, wherein is shown an embodiment of the present invention, but it is to be understood that changes, variations and modifications may be resorted to which come within the scope of the claims hereunto appended.

In the drawing wherein like numerals of reference designate corresponding parts throughout the several views:

Figure 1 represents a front view of a rotary

2

pump constructed in accordance with the invention in which one half is shown in outline and the other half is shown in cross-section on line 1—1 in Figure 2.

5 Figure 2 is a side view of Figure 1 taken on line 2—2 in Figure 1.

Figure 3 is an isometric view of the rotary drum constructed in accordance with the invention.

10 Figure 4 is an isometric view of the cylindrical double spring member as used in the invention.

Figure 5 is an isometric view of one of the cylindrical roller pistons.

15 Figure 6 represents an outline front view of the device, the front bracket being removed and the supporting legs broken away.

Figure 7 is a fragmentary side view of the rotary drum showing the cylindrical roller pistons in position and mounted within the drum and extending outwardly of the drum and contacting the inner peripheral bore of the piston housing.

20 Referring now more particularly to Figure 2 of the drawing, the rotary pump comprises in general a piston housing 10, a rotary piston drum 11, the front bracket 12, the rear bracket 13, the cylindrical roller pistons 14 and the cylindrical spring sleeve 33.

The said piston housing 10 may take any form consistent with the use to which the mechanism is to be put and includes a cylindrical bore 16, an inlet port 17 and an outlet port 18. The inner ends of these ports are preferably enlarged as shown in dotted lines in Figure 1 and indicated by the numerals 19 and 20. These enlargements extend an appreciable distance of the bore 16, with the exception that 20 extends upwardly and 19 extends downwardly. This feature permits the pump to be reversed at will without any alterations.

25 The rotary piston drum 11, as best shown detailed in Figure 3, comprises a circular disc 21 provided with integral, upstanding guide blocks 22, radially arranged to provide a guideway 23 for the roller piston 14.

A drive shaft 24, preferably integral with the outside face 25 of said disc 21, extends centrally and outwardly and is provided with a ball bearing 26 in abutment with said outside face 25.

Another circular disc 27 is secured to the free ends 28 of said guide blocks 22 by means of screws 29, or the said disc 27 may be made integral with

50

the drive-shaft 24, disc 21 and guide blocks 22 if found convenient to do so.

The outer face 30 of said disc 27 is provided with a centrally disposed and outwardly extending, integral stub-shaft 31 which is adapted to receive a ball bearing 32.

The rotary piston drum 11, as shown in Figures 1, 3, 6 and 7 is designed to receive four of said rollers 14, of course, more or less roller pistons may be used if so desired.

The cylindrical roller pistons 14, as shown detailed in Figure 5, are of such diameter that all four rollers will contact the interior cylindrical bore 16 of the piston housing at the same time. This is accomplished, in order to provide a constant positive tendency to thrust the roller pistons 14 outwardly and in contact with the bore 16 of the housing 10, by means of a cylindrical spring member 33, such as shown detailed in Figure 4.

This spring member 33 is positioned centrally within said drum 11 and in positive contact with the four rollers 14 freely confined in the guide-ways 23 between the upstanding guide blocks 22 of the drum 11 as shown in Figures 1, 6 and 7.

The aforesaid cylindrical spring member 33 comprises an inner cylindrical spring 34 which is snugly surrounded by an outer cylindrical spring 35.

This inner cylindrical spring 34 may be made from any appropriate springsheet material and formed to provide a longitudinal gap 36, while the outer cylindrical spring 35 snugly surrounds the inner spring 34 and is provided with a biased gap 37 (Figure 4) of substantially helical configuration.

Assembled, the discs 21 and 27 of said rotary piston drum 11 as well as the guide blocks 22 are finished to form a smooth cylindrical surface 38.

The front bracket 12 comprises an annular cover for the piston housing 10 having a reduced, annular outer portion 39. The inner face 40 of said front bracket 12 is provided with an eccentric counterbore 41 deep enough to accommodate the disc portion 21 of the drum 11, so that when the latter is in assembled position, the inner face 40 of the front bracket 12 comes in perfect alignment with the inner face 42 of the drum 11.

The aforesaid reduced outer annular portion 39 is provided with a common stuffing box 43 which is relied upon to seal the pump of any liquid escaping from the interior of the pump.

The rear bracket or cover 13 comprises a circular cover for the piston housing 10 having a reduced portion 44. The inner face 45 of said rear bracket 13 is provided with an eccentric counterbore 46 to accommodate the disc 27 of the drum 11, when assembled.

Of course it is well to note that the eccentric counterbore 41 of the front bracket or cover 12 and the eccentric counterbore 46 of the rear bracket 13 are in alignment, when assembled, and in eccentric relation with the bore 16 of the piston housing 10.

The front and rear brackets 12 and 13 respectively are also provided with a counterbore 47 and 48 in which the ball bearings 26 and 32 respectively are mounted.

In order to secure the pump to a suitable base, legs 49 are provided. These legs may be integral with the brackets 12 and 13, as shown, or they may be integral with the piston housing 10, or otherwise.

Obviously lubricant may be introduced to the ball bearings 26 and 32 through openings 50 and

51 respectively and to the outer faces 25 and 30 of the discs 21 and 27 respectively of the rotary drum 11 and therefore to the eccentric counterbores 41 and 46 in which the discs as part of the drum 11 rotates.

Located in each roller guide-way 23 of the drum 11 is a cylindrical roller piston 14 which fits snugly therein, and also between the inner faces 40 and 45 of front bracket 12 and rear bracket 13, respectively.

The operation of my rotary pump is as follows: Assuming that the inlet port 17 is connected by suitable piping to a liquid supply and the outlet or discharge port 18 connected to a distributing system which may be a pipe leading to a reservoir or other suitable means.

When the pump is operated in either direction by manually rotating the piston drum-shaft 24 or by motive power if so desired, the drum 11, of course, also rotates and with it the roller pistons 14, and since the piston drum 11 and the piston housing 10 are mounted in eccentric relation, a crescent shaped space 52 is thus created therebetween.

25 While the piston drum 11 rotates, the roller pistons 14 roll in and outwardly of the guide-way 23 between the guide-blocks 22 of the drum 11 and on account of the cooperative arrangement of the roller pistons 14 and the cylindrical spring member 33, the roller pistons 14 are always in positive contact with the peripheral surface of the bore 16 of the piston housing 10.

At this time, I desire to call special attention to the fact that the herewith described roller pump is not of the type in which the roller pistons 35 depend on centrifugal force to contact the inner surface of the cylindrical bore in the housing so they may form a sealed space during its contact.

As previously described the roller pistons in my invention are continuously in contact with the bore 16 of the piston housing 10 thereby forming a sealed space between the roller pistons 14 and the bore 16 of housing 10, and owing to the eccentric mounting of the piston drum 11 in which 45 the roller pistons operate in the piston housing 10, the sealed space between the roller pistons and the bore 16 is increased in volume as the drum 11 is rotated thus producing a suction which lifts the liquid and causes it to flow into the port 50 17 or 18, depending in which direction the pump is being rotated, where it enters and fills the space between the roller pistons 14 and the housing bore 16.

As the piston drum 11 rotates, the other roller piston comes into operative position relative to the intake port and as it passes the point 53 of the crescent shaped space 52 between the periphery of the bore 16 in housing 10 and the drum 11 attenuation will be provided to suck or draw fluid in.

As the crescent space decreases towards the outlet, the effect of the roller pistons will be to build up pressure in the fluid and force the same through the outlet port under increased pressure.

65 The maximum pressure under which the pump operates can be varied by varying the speed of rotation of the piston drum.

In the above specification the pump has been described with relation to the rotary drum having four roller pistons operating therein, but it is evident that any number of rollers can be used.

While a preferred specific embodiment of the invention is hereinbefore set forth it is to be clearly understood that I am not limited to the exact construction illustrated and described, be-

cause various modifications of the details may be provided in putting the invention into practice within the purview of the appended claim.

I claim:

A rotary pump comprising a housing provided with a cylindrical bore; intake and discharge ports leading to said bore, covers for said housing, a piston drum supported for rotation in said covers in eccentric relation to the bore of said housing, said drum being provided with a plurality of radial guide ways, each of said guide ways adapted to accommodate rotatably and slidably a horizontally disposed cylindrical roller piston, and centrally disposed means for urging said roller pistons uniformly against the wall of the bore of said housing, said means comprising two hollow coaxial resilient cylindrical members of which the inner one is telescoped into the outer

5 member, each having one gap extending throughout their length, the said gap of said outer member being helical.
